Primary Examiner—Celia Murphy*Attorney, Agent, or Firm*—Randall C. Brown; Locke Purnell Rain Harrell[57] **CLAIM**

The ornamental design for an insulated water bottle carrier, as shown and described.

DESCRIPTION

FIG. 1 is a perspective view of an insulated water bottle carrier showing my new design, the broken lines showing a water bottle as well as broken lines showing vertical release mechanisms in FIGS. 1, 3 and 5, being for illustrative purposes only and forming no part of the claimed design; FIG. 2 is a front elevational view thereof; FIG. 3 is a right side elevational view thereof; FIG. 4 is a rear elevational view thereof; FIG. 5 is a left side elevational view thereof; FIG. 6 is a top plan view thereof; and, FIG. 7 is a bottom plan view thereof. The broken lines shown on the straps and carrier portion of the claimed article throughout the views are understood to represent conventional stitching.
